UNITED STATES PATENT OFFICE.

GEORGE H. BARTLE, OF NEW YORK, N. Y., ASSIGNOR TO ARTHUR L. KUGEL, OF BROOKLYN, NEW YORK.

DESIGN FOR A CAP FOR A PENCIL OR SIMILAR ARTICLE.

Application filed November 17, 1923. Serial No. 7,808. Term of patent 14 years.

To all whom it may concern:

Be it known that I, GEORGE H. BARTLE, a subject of the King of Great Britain, residing in the city, county, and State of New York, have invented a new, original, and ornamental Design for Cap for a Pencil or Similar Article, of which the following is a specification, reference being had to the accompanying drawing, forming a part thereof.

Figs. 1 and 2 are views showing the cap for a pencil in elevation, mounted on a pencil indicated in dot and dash lines, Fig. 2 being taken at a different angle; and Figures 3 and 4 are, respectively, top and bottom plan views of the cap for a pencil.

What I claim is—

The ornamental design for a cap for a pencil or similar article as shown.

GEORGE H. BARTLE.
